[57] CLAIM

The ornamental design for a combined flashlight and
blinker, as shown and described.

DESCRIPTION

FIG. 1 is a front elevational view of a combined flash-
light and blinker showing my new design, shown in an
extended position;

FIG. 2 is a front elevational view thereof;

FIG. 3 is a side elevational view thereof;

FIG. 4 is a rear elevational view thereof;

FIG. 5 is a bottom plan view thereof;

FIG. 6 is a top plan view thereof; and,

FIG. 7 is a sectional view thereof.

*Fig. 1.**Fig. 2.**Fig. 3.**Fig. 4.**Fig. 7.**Fig. 5.**Fig. 6.*
